(57) **CLAIM**

I claim the ornamental design for an egg holder, as shown and described.

DESCRIPTION

FIG. 1 is a top perspective view of an egg holder, showing my new design.

FIG. 2 is a front elevational view of the egg holder.

FIG. 3 is a rear elevational view of the egg holder.

FIG. 4 is a left side elevational view of the egg holder.

FIG. 5 is a right side elevational view of the egg holder.

FIG. 6 is a top plan view of the egg holder.

FIG. 7 is a bottom plan view of the egg holder; and,

FIG. 8 is a top perspective view of the egg holder, shown with a removable tray in broken lines.

The egg holder is shown with a symbolic break in its length. The appearance of any portion of the article between the break lines forms no part of the claimed design. The broken lines on the interior of the egg holder show portions of the article forming no part of the claimed design. The broken lines illustrating a removable tray in FIG. 8 are for the purpose of showing environment and form no part of the claimed design.
